METHOD OF AND MACHINE FOR ALTERING
A STEEL ROPE

Henry Allyn Wood, Berkeley, Calif.

Application August 23, 1933, Serial No. 686,473

10 Claims. (CL 117—1)

The present invention relates to a method of and machine for altering a steel rope, and its principal object is to provide a method of and means for spreading a previously manufactured steel rope into its constituent parts, effecting a desired change in the parts while thus spread and again twisting the parts into a rope in a continuous operation.

In a steel rope manufacturing plant a problem frequently arises in connection with the altering of steel rope already manufactured. Steel rope consists of a core and a plurality of strands twisted about the core, each strand in turn again consisting of a plurality of single wires twisted into a strand.

It frequently happens that it becomes desirable to alter the constituent parts of a steel rope already manufactured. A steel rope may have been made with a hemp core for instance, and the trade at that time may call for a steel rope having a steel core, which makes it necessary to either store the manufactured rope for a certain length of time until a steel rope with a hemp core is again called for by the market, or to change the rope from a hemp core to a steel core, a procedure which up to now was considered practically impossible to carry out.

It may also become necessary to exchange one of the strands of a steel rope already manufactured for a new strand or to change the number of strands, substituting for instance eight strands for a six strands, or vice versa.

It has also recently been proposed and a simple device has been developed for the purpose of pre-forming the strands of a rope before they are twisted into a rope, and it frequently becomes desirable to change a rope already manufactured out of strands that were not pre-formed into a rope with pre-formed strands.

It may also be desirable to splice two ropes in such a manner that the two ropes actually become a single rope wound on a single drum.

It is the object of the present invention to provide a simple means for solving all of these problems by means of a simple change in the standard steel rope making machine which allows a rope already manufactured to be untwisted into its constituent parts, the desired change to be effected and the new set of constituent parts to be retwisted into a rope in a continuous operation.

Further objects and advantages of my invention will appear as the specification proceeds.

The preferred forms of my invention are illustrated in the accompanying drawings, in which

Figure 1 shows a top plan view of a machine for preforming the strands of a rope already manufactured;

Figure 2 a side elevation of the machine;

Figure 3 a diagrammatic top plan view of a part of the machine arranged for changing the core of a rope;

Figure 4 a diagrammatic plan view of the machine arranged for splicing two ropes together;

Figure 5 a diagrammatic plan view of the machine arranged for adding additional strands to a rope and for changing the core;

Figure 6 a detail view in axial section of a rope feeding die; and

Figure 7 a detail view in plan of a mechanism for transmitting motion at variable speeds from one bobbin to another bobbin mounted coaxially therewith.

While I have shown only the preferred forms of my invention I wish to have it understood that various changes or modifications may be made within the scope of the claims hereto attached without departing from the spirit of the invention.

In connection with the drawings it should be noted that while the length of a standard wire twisting machine usually extends over several hundred feet, and comprises a large number of sections, depending upon the number of strands to be twisted into a rope, a large central section 30 has been omitted from each of the drawings as being unnecessary for an understanding of the invention and for the purpose of allowing the entire machine to be shown in single views.

Referring first to the form illustrated in Figures 1 and 2, a standard cage 1 comprising a plurality of rings 2 arranged in spaced and parallel relation and interconnected by an annular series of rods 3, preferably three in number, is revolvably supported on rollers 4, one set of spaced rollers 40 being provided for each ring and supporting the same at points evenly spaced from the vertical center line of each ring. The rollers on one side of the cage may be unconnected but the rollers on the opposite side are interconnected by means of a shaft 5 extending throughout the length of the cage and projecting to the right thereof as shown in Figure 1. This shaft is driven by means of a belt connection 6 from the motor 7. It will be noted that while this cage may consist of a large number of sections only the two end sections are shown in the drawings, and all the central sections are omitted. The end ring 2 on the right hand side is provided with a central hub 8, see Figures 1 and 6, having a sleeve 9 fixed

to the inside thereof, and the sleeve is formed with a pinion 10 meshing with either one of two bevel gears 11 and 12 mounted on a transverse shaft 13 supported in bearings 14, and this shaft is provided at one of its ends with a gear wheel 15 meshing with a lower gear wheel 16, which latter has a pinion 17 mounted coaxially therewith. This pinion 17 meshes with a large wheel 18 mounted on a transverse shaft 19 which has mounted thereon, on the opposite side of the machine, a large pulley 20.

The rope 21 which may be mounted on a spool not shown in the drawing is fed into the rear end of the machine (right hand side of the drawing) through a hollow shaft 22, passing axially through the sleeve 9 and suitably supported by a fixed standard 23, and the hollow shaft terminates inwardly in a standard die 24 including two semi-cylindrical elements 25 held together by means of two screws 26 (see Figure 6). The screws are threaded into opposite walls of a casing 27, the front end of which is closed by a plate 28 having an aperture registering with the aperture of the die, and tapering away therefrom as shown at 29.

The rods 3 of the cage are provided with peripherally spaced rollers 30 over which the strands 31 of the rope emanating from the die may be guided to run parallel to the rods throughout the length of the cage, the rings of which are formed in a conventional manner with suitable guide holes while at the opposite end of the cage a corresponding number of guide rolls 32 are provided. The end ring 2 of the cage on the left hand side is provided with a conventional twister head 33 including the pre-forming head 34, which latter is not my invention and which simply comprises three rollers 35 for each strand arranged in close relation so that the strand passes between the first and second roller and back again between the second and third roller whereby a twist is imparted to the strand corresponding to the twist subsequently applied by the twisting operation. From the pre-forming head the individual strands pass through the conventional closing die 36, and while passing they are twisted into a rope, and this new rope 21' passes over the wheel 37 and back again alongside of the machine over the pulley 20 around which it is wound several times, and finally fed on the drum 38.

It should be noted that most of the parts of this machine are of standard construction, particularly as far as they refer to the twisting of a plurality of strands into a rope, and that the principal novelty of my invention consists in adding to the standard twisting machine means for untwisting a rope previously formed and for feeding the rope through the machine so as to allow certain changes to be brought about while the strands of the rope are separated from one another.

I show in connection with Figures 1 and 2 a standard cradle 39 for each of the sections of the cage but where the sole object of the operation is to preform the strands of a rope previously made, the cradles need not be provided since the entire operation consists in pulling the rope through the device by means of the pulley 20, untwisting the strands at the die 24, passing the untwisted strands individually through the pre-forming head 34, and retwisting the same at the closing die 36. In case it should happen that there is a slight variance in the tension of the individual strands the rollers 30 may be adjusted lengthwise of the rods 3 to take up any slack occasioned by the unequal tension. During the en-

tire operation the core may be drawn through the device through central openings in the rings 2.

Where it is desired to exchange the old core for a new one, either for a core of the same character or of a different character, the device illustrated in Figure 3 may be used, it being understood, of course, that this device may be used in the combination shown in Figure 1, if it is desired to both substitute a new core and to preform the strands. In the schematic view of Figure 3 the rope 21 passes through the die 24 and is untwisted by the revolving case 1 into the strands 31 which are guided over the rollers 30. The core 31' may be guided through the device centrally or partly along the rim by means of rollers 40 to be finally fed through a central sleeve 41 into the end section of the cage where it is removed, and a new core substituted therefor by the mechanism shown in Figure 3 and with greater detail in Figure 7. In this section one of the conventional cradles 20 39 is provided, the cradle being supported in front and rear bearings 44, and being underslung to remain in stationary position by gravity when the cage revolves. A shaft 45 is supported transversely in the cage and is provided with two bobbins 46 and 47, the former being intended to take up the old core, while the latter provides the new core. The bobbin 47 is revolved by the pull exercised on the new core by the pulley 20 and revolving motion is imparted from the bobbin 47 to the bobbin 46 at a variable speed since the speed ratio between the two bobbins will change continuously during the operation. Any suitable method for accomplishing this transmission may be used. As illustrated in Figure 7 I provide a jack shaft 48 running parallel to the shaft 45. Both of the bobbins are loose on the shaft 45 and the latter shaft has a wheel 49 fixed thereto, motion being transmitted from the shaft 45 to the shaft 48 at increased speed through the chain 53 and from the shaft 48 to the bobbin 46 through a chain 54 and a clutch arrangement shown at 55. The friction between the wheel 49 and the friction clutch 52 is sufficient to effect rotation of the bobbin 46 for holding the core taut. The core is preferably fed on the bobbin 46 through a reciprocating guide 56 well known in the art and not illustrated in detail. While the old core is thus fed upon the bobbin 46, a new core is fed from the bobbin 47 into the closing die 36 in central relation to the strands which are twisted into a rope by the revolving movement of the cage, the rope being advanced in the manner described in connection with Figures 1 and 2. It will be noted that in this manner, by a simple operation, a new core is substituted for the old one. A suitable tensioning device or automatic take-up for any slack may be provided in the springs 57 attached to a sleeve 58 and rollers 59 placing the individual strands under tension.

In Figure 4 my invention is used for the purpose of splicing two ropes together, and for winding the combined ropes upon a single spool. In this form the two ropes indicated at 21' and 21'' have their ends introduced into the cage from opposite ends thereof through the dies 36 and 24 respectively. Both of the ropes are untwisted by means of the revolving cage as illustrated in the drawings and the separate strands of the two ropes are brought together and spliced in a manner well known in the art with a number of wires of one 75

strand accommodated in registering grooves of an opposing strand and welded to corresponding wires of such strands in such a manner that the splice is absolutely unnoticeable. After all the 5 strands have been spliced the machine is set in motion and the spliced ends and the entire rope 21" is pulled through the machine and wound upon the drum of the rope 21', it being apparent that while the strands are in separated condition 10 any other desired operation may be performed on the same, such as the pre-forming of the strands or the substitution of a new core, or the substitution of a new strand for an old one, or even the addition of new strands if such should 15 be desired.

The device illustrated in Figure 5 provides in addition to the core-changing means heretofore described, means for adding additional strands to the rope. This means consists simply in providing 20 two additional cradles 39, each serving as supporting means for a bobbin 60, from which additional strands 61 are fed over suitable rollers 62 to join the other strands at the closing die 36, and to be twisted into a rope with the same. In 25 this figure, which as a whole is a diagrammatic plan view of the machine, the feeding spool 63 is shown diagrammatically in side elevation to bring out the idea that the supporting elements 64 for the spool are revolvably mounted as shown at 65, so that the spool may be slowly revolved transversely by means of a handle 66 as the rope is 30 withdrawn therefrom.

I claim:

1. In a machine of the character described, 35 two spaced dies for guiding a rope, means for pulling the rope through the dies and means interposed between the dies for untwisting and re-twisting the rope, the said means having means associated therewith for substituting new parts for certain constituent parts of the rope.

2. In a machine of the character described, two spaced dies for guiding a rope, means for pulling a rope through the dies and means interposed between the dies for untwisting and re-twisting 45 the rope, the said means having means associated therewith for pre-forming the constituent parts of the rope.

3. In a machine of the character described, two spaced dies for guiding a rope, means for 50 pulling a rope through the dies and means interposed between the dies for untwisting and re-twisting the rope, the said means having means associated therewith for substituting a new part for one of the constituent parts of the rope.

4. In a machine of the character described, two spaced dies for guiding a rope, means for pulling a rope through the dies and means interposed between the dies for untwisting and re-twisting 55 the rope, the said means having means associated therewith for removing one of the constituent parts from the rope.

5. In a machine of the character described, two

spaced dies for guiding a rope, means for pulling a rope through the dies and means interposed between the dies for untwisting and re-twisting the rope, the said means having means associated therewith for adding constituent parts to the 5 rope.

6. The method of untwisting a rope into its constituent parts, of substituting new parts for certain constituent parts and of re-twisting the new and old parts into a rope in synchronized 10 order.

7. A machine for untwisting and twisting a rope comprising an elongated cage revolvable about its longitudinal axis, a rope entrance at one end of the cage and a rope exit at the other 15 end, and means carried by the cage for untwisting the rope into its constituent parts and for again twisting the rope back into its original form, and means for removing a part of the rope and for substituting a new rope part for the one 20 being removed, said means feeding out the new part as needed, and winding up the old part as it is freed from the incoming rope.

8. A machine for untwisting and twisting a rope comprising an elongated cage revolvable 25 about its longitudinal axis, a rope entrance at one end and a rope exit at the other end, guides for supporting rope parts after these parts have been untwisted from the rope, said guides extending parallel with and being spaced from the 30 cage axis, whereby access can be had to each separate portion of the rope as it passes through the cage, the same rotation of the cage which untwists the rope at the entrance end being used for twisting the rope parts back into the original 35 rope.

9. A machine for substituting a new core for one in the rope and comprising an elongated cage revolvable about its axis, said cage having a rope entrance at one end and a rope exit at the 40 other end, means carried by the cage for untwisting the strands from the core at the entrance end, means for winding the old core on a spool as it is freed from the rope, means for feeding a new core to the exit end of the machine, the rope untwisting means winding the strands around the new core at the exit end for providing the rope with a new core.

10. A machine for substituting a new strand for one in the rope and comprising an elongated 50 cage revolvable about its axis, said cage having a rope entrance at one end and a rope exit at the other end, means carried by the cage for untwisting the strands at the entrance end, means for winding the strand to be discarded on a spool as 55 it is freed from the rope, means for feeding a new strand to the exit end of the cage, the rope untwisting means winding the new strand with the other parts of the rope at the exit end for providing the rope with a new strand. 60

HENRY ALLYN WOOD.
